UNITED STATES PATENT OFFICE.

IRVING SONNENTHAL, OF NEW YORK, N. Y.

HOOK LATCH.

Application filed January 4, 1922. Serial No. 527,003.

To all whom it may concern:

Be it known that I, IRVING SONNENTHAL, a citizen of Poland, and a resident of New York city, borough of Manhattan, in the county and State of New York, have invented certain new and useful Improvements in Hook Latches, of which the following is a full, clear, and exact description.

Among the principal objects which the present invention has in view are: to provide an improved hook latch over the one for which a Patent No. 1,370,711 was granted to me on March 8, 1921, cross reference to which is here made; to prevent the accidental release of the latch; to provide a strong, neat and simply constructed latch of the character mentioned.

Drawings.

20 Figure 1 is a plan view of a latch constructed in accordance with my present invention, the latch being shown in conjunction with the fragment of a wrist-band and watch, and in locked position.

25 Figure 2 is a sectional elevation of the latch and a portion of the ribbon as seen in Figure 1, the section being taken on the longitudinal center.

30 Figure 3 is a view of the latch similar to that shown in Fig. 2, the latch being shown in open position.

Figure 4 is a plan view of the latch shown in closed position.

35 Figure 5 is a plan view of the latch shown in open position.

Figure 6 is a section taken on the line 6-6 of Figure 5.

40 Figure 7 is a plan view of the development of the ribbon engaging member of the latch.

Figure 8 is a plan view of the movable watch engaging member shown in development.

Description.

45 The latch herein disclosed is particularly adapted for use with wristbands constructed of ribbon or other flexible material and comprises essentially two separate parts, 50 one of which, the hook member 10 is fastened to the wristband 11 and the other or sliding member 12 of which is mounted to slide on the hook member 10.

In developing the hook member 10 a

metal stamping of the configuration shown 55 in Fig. 7 having ribbon engaging slots 13 is shaped to provide a projection which when bent up forms a hook 14, and wings 15, the edges of which when turned inwardly act as a guideway for the sliding member 12. 60

Referring to Figure 8, the development of the sliding member 12 comprises a T-shaped stamping having arcuate wing portions 16 formed at the junction of the upright and cross member of the T. The upright when bent forms a hook 17 which is engaged by the watch ring 18 as will be hereinafter explained. The remainder of the T is bent on the dotted lines to form a hood 19, the portions 20 forming feet which are disposed beneath the wings 15 of the hook member when assembled, the portions 21 forming the sides, 22 the top and 23 the back of said hood. When the bending has been done, a part of the upright of the T will form the 75 bottom. The wings 16 are then bent against the portions 21 and their straight edges will be spaced slightly from the feet portions 20. This will allow the guide forming wings 15 to fit therebetween. 80

The sliding member 12 thus formed, is assembled to the hook member 10 in position so that the hooked portion 17 on the former can be forced beneath the end of the hook 14 on the latter. This provides for a 85 lock because the space between the end of the hook 17 and the edge of the hood 12 will just permit the insertion therebetween of the watch ring 18, so that when the hook 17 passes beneath the end of hook 14, the ring 90 can not be withdrawn.

In order to further lock the ring in place, a slight pull will cause the hood 12 to move forwardly, the top of it passing over the end of the hook 14 and riding up on the top 95 of said hook will bend it down sufficiently to prevent the hook 17 on the sliding member from being withdrawn.

The wings 15 are bent as at 24 to provide stops to limit the rearward movement of the sliding member and prevent its accidental separation from the hook member 10. The latch may be used in many services. One service for which it is particularly adaptable is in conjunction with wrist or other watches in which a ribbon is the supporting means. 100 105

It will be observed that the normal tendency of the hood 12 and parts associated

therewith is to assume the position where the latch is closed, and from which it is difficult to remove by accident the watch ring 18.

5

Claims.

1. An article as characterized comprising a member having guides formed therein; a guard hook formed on said member; a member adapted for movement between said guides; means at the sides of said guard member for extending above and below the guides to slidably mount the guard member thereon, and a hook formed on said movable member, said hook being capable of forcibly entering said first mentioned hook.

2. An article as characterized comprising a member having a hook formed thereon; side wings for said member and bent to provide guides extending inwardly over said member, a guard member slidably longitudinally on said first mentioned member; side wings on the guard member bent beneath said guides to retain the guard member in sliding engagement with the first mentioned member, and a hood formed on said slidable member for engaging the hook on said first

mentioned member and depressing the end thereof.

3. An article as characterized comprising a hooked member; a hooded member slideable on said hooked member; means on said hooded member for retaining a watch ring; guide wings formed on said hooked member; the hood member having movement between said guide wings, extensions on said hooded member disposed beneath said guides to retain said hooded member in association with said hooked member, and side tongues for said hood member extending in overlapping and crossed relation to said extensions and positioned above the guides when the hood member is in sliding engagement with the hooked member.

4. An article as characterized, comprising a hooked member; guides formed on said member; a hooded member formed to comprise slots through which the edges of said guides extend; a hook formed on said hooded member adapted to be engaged by a loop, said hook being capable of retaining said loop when moved into the hooked portion of the first mentioned member.

IRVING SONNENTHAL.
